UNITED STATES PATENT OFFICE

LAURENCE P. DICKEY, OF MOUNTAIN LAKES, NEW JERSEY, ASSIGNOR TO AUGUST GOERTZ & CO., INC., A CORPORATION OF NEW JERSEY

VANITY BOX

Application filed October 26, 1929. Serial No. 402,568.

This invention relates, generally, to improvements in vanity boxes or compacts for carrying cosmetic materials.

The invention has for its principal object 5 to provide a vanity box or compact comprising body sections arranged to close one upon the other, one of said body sections having a novel retaining clip fixed therein, said retaining clip being constructed and arranged 10 to removably retain a cosmetic refill within said body section.

Another object of the present invention is to provide a novel vanity box retaining clip of the above character which enables 15 the easy and ready insertion of a cosmetic refill into the vanity box and which retaining clip positively and reliably retains the refill therein while permitting the easy removal of used refills when desired.

20 Other objects of this invention, not at this time more particularly enumerated, will be clearly understood from the following detailed description of the same.

Fig. 1 is a plan view of a vanity box made 25 according to and embodying the principles of the present invention; the body sections thereof being shown in open relation;

Fig. 2 is a part longitudinal sectional view 30 of Fig. 1 taken along line 2—2 of Fig. 1;

Fig. 3 is a plan view of a novel retaining clip employed in the invention.

Similar characters of reference are employed in all of the hereinabove described 35 views to indicate corresponding parts.

Referring now to said drawings, the reference character 6 indicates a lower body section of the vanity box, and 7 an upper body section thereof. Said body sections are 40 respectively provided along their meeting rear edges with hinged knuckles 8 which interfit one with another to receive a hinge pin 9 whereby said sections are hingedly connected together so as to close one upon the other. The periphery of the section 7 is provided, at the point thereof opposite its hinge connection with the lower body section 6 with a lip 10 which is adapted to cooperate with a tongue 11 provided on a catch 12 which is positioned at the corresponding

point of the periphery of the lower body section 6. The lip 10 and the catch 12 when engaged serve to interlock the sections 6 and 7 in closed relation.

According to the preferred embodiment 55 of the invention, a three pronged retaining clip 13 of substantially triangular shape in plan, is positioned within the lower body section 6. Retaining clip 13 is illustrated as provided with an aperture 24 at its central portion to receive a rivet 14 that secures this clip to the outer wall of body section 6. It is to be understood, however, that the retaining clip may be secured in position in the lower body section by other means, such as by spot welding. The three prongs 15, 16 and 17 extend outwardly from the center of the retaining clip in surface contact with the inner surface of the body section 6 and have circumferentially disposed slightly 60 outwardly off-set refill supporting shoulders 18 formed on the end portions of these prongs. From the shoulders 18 prongs 15, 16 and 17 extend outwardly and slightly 65 inwardly radially, forming bezels 20 adapted for the reception and retention of the marginal edge portions of compact refill 21. Prongs 15, 16 and 17 terminate in curved 70 radially outwardly directed ends 19 which facilitate the easy insertion of the compact 75 refill into body section 6 by guiding the refill centrally of the retaining clip during 80 such insertion.

The prongs 15, 16 and 17 being spaced 120 degrees apart provide for a three point support of the refill resulting in a stable mounting of the same. The off-set supporting shoulders 18 and the end portions of the prongs possess considerable resiliency which 85 also facilitates the insertion or removal of a refill. Prongs 15, 16 and 17 terminate radially inwardly of the inner side wall surfaces 90 of the lower body section, thereby enabling the free outward movement of the end portions of these prongs as the refill is inserted into the retaining clip. Also this spacing of the end portions of the prongs from the interior surface of the side walls of this body 95 section, provides a space between the body 100

section and the refill for the insertion of a tool to effect the removal of the latter.

10 The upper body section 7 is provided with a mirror inlay frame 23 that is frictionally retained within this body section and retains a mirror 24 therewithin. When the body sections are in closed positions, a suitable space is provided between the mirror 24 and the refill 21 to accommodate an applicator.

15 It will be noted that the novel vanity box of this invention provides a refill retaining clip of extremely simple construction which is retained in fixed position within the vanity box body section and which has terminal prong portions suitably spaced from the walls of the body section to not only enable adequate yielding of the prongs to accommodate the insertion of the refill but also to provide 20 a suitable space to enable the easy insertion of an instrument for effecting the removal of a used refill.

25 The resilient engagement of the bezels 20 with the marginal edge portions of the compact refill prevents objectionable turning of the refill with respect to the clip 13 when an applicator is rubbed around on the refill, whereas any tendency for the clip 13 to turn is prevented by the positive holding action 30 of rivet 14.

35 As many changes could be made in the above construction and many apparently widely different embodiments of this invention could be made without departing from the scope thereof, it is intended that all matter contained in the above description or shown in the accompanying drawings shall be interpreted as illustrative and not in a limiting sense.

40 What is claimed is:—

1. A vanity box comprising, a lower body section and a cooperating upper body section, a pronged cosmetic refill retaining clip positioned within said lower body section, said retaining clip having a central portion secured to the inner bottom surface of said lower body section and prongs radiating outwardly from said central portion, said prongs having free resilient end portions for yieldably retaining the marginal edges of a cosmetic refill.

55 2. A vanity box comprising, a lower body section and a cooperating upper body section, a pronged cosmetic refill retaining clip positioned within said lower body section, said retaining clip having a central portion secured to the inner bottom surface of said lower body section and prongs radiating outwardly from said central portion, said prongs having free resilient end portions for yieldably retaining the marginal edges of a cosmetic refill, said end portions terminating radially inwardly of the inner side wall surfaces of said lower body section, thereby providing for the free outward movement of

said end portions during the insertion or removal of a cosmetic refill.

3. A vanity box comprising, a lower body section and a cooperating upper body section, a pronged cosmetic refill retaining clip positioned within said lower body section, said retaining clip having a central portion riveted to the bottom of said lower body section and prongs radiating outwardly from said central portion, said prongs having resilient end portions comprising circumferentially disposed outwardly offset refill supporting shoulders and bezels formed adjacent said shoulders for yieldably retaining the marginal edge portions of a refill in contact with said shoulders.

4. A vanity box comprising, a lower body section and a cooperating upper body section, a pronged cosmetic refill retaining clip positioned within said lower body section, said retaining clip having a central portion riveted to the bottom of said lower body section and prongs radiating outwardly from said central portion, said prongs having resilient end portions comprising circumferentially disposed outwardly offset shoulders providing a three point support for a refill and bezels formed adjacent said shoulders for yieldably retaining the marginal edges of a refill in engagement with said shoulders, said prongs terminating in radially outwardly curved ends spaced from the side walls of said lower body section and providing for the easy insertion and removal of a refill.

5. In testimony that I claim the invention set forth above I have hereunto set my hand this 25 day of October 1929.

LAURENCE P. DICKEY.
